QUATERNARY HALIDES OF CERTAIN TROPANE ALKALOIDS

Robert Goodman Johnston and Kenneth Eric Vincent
Spencer, Edinburgh, Scotland, assignors to T. & H.
Smith Limited, Edinburgh, Scotland, a British company

No Drawing. Application April 12, 1957
Serial No. 652,374

Claims priority, application Great Britain May 1, 1956
14 Claims. (Cl. 167—58)

The present invention concerns improvements in and relating to quaternary salts and solutions thereof. It is particularly concerned with novel quaternary salts of tropine esters and pseudo-tropine esters and with their preparation and use as hypotensive agents.

It is often most desirable in surgical operations to produce controlled hypotension. This can be done by the intravenous infusion of substances which are termed hypotensive agents, one example of which is hexamethonium dibromide.

It is an object of the present invention to produce new quaternary salts having hypotensive activity.

It is another object of the invention to produce solutions which can be administered to patients by intravenous infusion in order to reduce blood pressure during surgical operations.

It is a further object to provide quaternary salts of tropine esters and pseudo-tropine esters which have valuable therapeutic properties.

With these and other objects in view the present invention provides quaternary salts of esters selected from the group consisting of tropine esters and pseudo-tropine esters, said quaternary salts having the general formula:

wherein:

X represents the anion of an acid, especially an inorganic acid,

n represents the valency of the anion X,

Y represents an organic carboxylic acyl group, and

Q represents the non-metallic atoms necessary to complete a heterocyclic radical, especially an unsubstituted 5-membered heterocyclic radical of the general formula C4H3D (wherein D represents a divalent member selected from the group consisting of —S—, —O— and —NH—).

These quaternary salts may be termed heterocycloylmethyl acyltropinium salts and heterocycloylmethyl acylpseudo-tropinium salts, respectively. The term "heterocycloylmethyl" is used to designate the group

wherein Q has the values given above.

As is known, tropine and pseudo-tropine are trans-cis-isomers and neither they nor their quaternary salts can be differentiated by plane formulae. Tropine is generally considered to be the trans form.

The preferred quaternary salts are halides, especially those in which the halogen has an atomic weight greater than 19, i.e. the chlorides, bromides and iodides.

Halides which may be used are 2-haloacetylthiophenes, 2-haloacetylfurans and 2-haloacetyl pyrroles.

The preferred tropine ester is homatropine, i.e. the ester of mandelic acid (phenylglycollic acid).

The preferred pseudo-tropine ester is phenyl-acetyl-pseudo-tropine.

2

The process of the present invention comprises preparing a quaternary halide of an ester selected from the group consisting of tropine esters and pseudo-tropine esters by reacting an organic carboxylic ester of tropine or of pseudo-tropine with a heterocycloylmethyl halide of the general formula:

10 wherein Q and X have the values given above, preferably in an inert solvent, and preferably with the aid of heat. The reaction takes place on leaving the reactants in contact with one another and heat is not essential, although it accelerates the reaction. The presence of a diluent is not essential although it facilitates the production of the quaternary halide.

From the resulting quaternary halides, preferably the chlorides, quaternary salts of other acids can be made. A number of general methods are available for this, three of which are as follows:

(a) Double decomposition of an aqueous or aqueous alcoholic solution of a quaternary chloride with a soluble alkali metal salt such as sodium bromide or iodide.

(b) Metathesis of a quaternary halide with, for example, a silver salt, preferably in alcohol.

(c) Reaction of an alcoholic solution of a quaternary halide with an acid in presence of an organic epoxide. This method is described by O. Sackur in Bull. Soc. Chim., 1952, 796.

30 The quaternary salts of the present invention have useful therapeutic properties. When injected into the human blood stream they exhibit to a very useful degree the power to block transmission of nervous impulses across sympathetic ganglia and cause a fall in blood pressure. Some at least of the quaternary salts, especially 2-thenoylmethyl homatropinium bromide, 2-thenoylmethyl phenylacetyl tropinium bromide and 2-furoylmethyl phenylacetyl tropinium bromide, exhibit a hypotensive action which exceeds that of hexamethonium dibromide.

35 The duration of action is much less than that of hexamethonium dibromide. The hypotension produced can readily be antagonised, when required, by adrenaline or methedrine. The quaternary salts are thus useful for producing controlled hypotension, for example during surgical operations.

40 45 Their hypotensive potency can be compared by measuring the reduction in the extent of contraction of the nictitating membrane of the cat in response to the stimulation of the preganglionic fibres of the cervical sympathetic nerve.

50 55 The heterocycloylmethyl quaternary salts of pseudo-tropine carboxylic esters appear, in general, to have a lower hypotensive potency than the corresponding heterocycloylmethyl quaternary salts of tropine carboxylic esters. Nevertheless, many of them have a very useful potency when measured in the above way. The relative potencies of twelve typical heterocycloylmethyl quaternary salts, some derived from tropine esters and the others from pseudo-tropine esters, were as follows:

	Quaternary salt	Potency	
2	thenoylmethyl homatropinium bromide	400	
2	thenoylmethyl phenylacetyl tropinium bromide	100	
2	thenoylmethyl tropyl tropinium bromide	50	
65	2	thenoylmethyl phenylacetyl-pseudo-tropinium bromide	20
2	thenoylmethyl benzoyl tropinium bromide	30	
2	thenoylmethyl benzoyl-pseudo-tropinium bromide	15	
2	thenoylmethyl isobutyryl tropinium bromide	9	
2	thenoylmethyl isobutyryl-pseudo-tropinium bromide	4	
2	furoylmethyl phenylacetyl tropinium bromide	33	
2	furoylmethyl phenylacetyl-pseudo-tropinium bromide	11	
70	2	pyrrolylmethyl phenylacetyl tropinium bromide	18
2	pyrrolylmethyl phenylacetyl-pseudo-tropinium bromide	8	

By way of comparison, the potency of hexamethonium dibromide was 10.

The heterocycloylmethyl quaternary salts of tropine carboxylic esters and of pseudo-tropine carboxylic esters are thus useful for producing controlled hypotension, for example during surgical operations.

As regards the preferred quaternary salts, the chlorides, bromides and iodides, the potencies of these three salts of the same tropine or pseudo-tropine carboxylic esters are the same, but their solubility in water is very different. The chlorides are the most soluble and the iodides the least. The chlorides are therefore generally more convenient for use as hypotensive agents in surgical operations.

In making the heterocycloylmethyl acyltropinium and acyl-pseudo-tropinium halides, it is preferred to use inert solvents of a polar nature such as ketones. The halides referred to are highly reactive and it is not therefore essential to heat the reaction mixture, as a good yield may be obtained by allowing the mixture to stand for a sufficient period of time at room temperature. It is preferred, however, to heat the reactants as the formation of quaternary salts is then rapid.

The invention will be illustrated by, but is not limited to, the following examples.

Example 1.—2-thenoylmethyl homatropinium bromide

5.0 gms. (0.0182 M) of homatropine were dissolved, with gentle warming, in 40 mls. of dry acetone. 25 mls. of a solution of 2-bromacetylthiophene (5.14 gms. 0.025 M) in acetone were added all at once, and the reaction mixture was allowed to stand 24 hours at room temperature. By this time a considerable amount of pale-tan solid had precipitated. After refluxing for 2 hours, the solid was filtered, ground under acetone, filtered and dried, giving 8.0 gms. (91%) of material, M.P. 190–193°. Two recrystallisations from acetone containing a small amount of isopropanol afforded 5.36 gms. (61%) of the salt, M.P. 197–198°, not changing on further recrystallisation and containing 16.59% bromide as compared to the theoretical figure of 16.69%.

Example 2.—2-furoylmethyl homatropinium chloride

Homatropine (20.0 gm.) and 2-chloroacetyl furan (11.6 gm.; 10% excess) were dissolved in 200 mls. dry acetone and allowed to stand in the dark at room temperature. After two days a syrupy lower layer had formed. 5 hours reflux on the steam bath resulted in production of a dark brown resin, which, after decanting the acetone layer and refluxing with dry benzene gave a brown powder (26.3 gm.) of low and indefinite M.P. (about 90° C.). This was repeatedly charcoaled in alcoholic solution and reprecipitated with ethyl acetate. This treatment gave a creamy-white solid which could now be recrystallised from ethanol and ethyl acetate. In this way 16.2 gm. (51%) white crystals were obtained, M.P. 187–8° C. The chlorine content was 8.45% as compared with a theoretical value of 8.26%.

Example 3.—2-pyrrolylmethyl homatropinium chloride

Homatropine (5.50 gm.) and 2-chloroacetylpyrrole (2.73 gm.; 10% excess) were refluxed three hours in 70 ml. acetone. Most of the acetone was removed in vacuo and replaced by dry benzene. The dark-brown precipitate so obtained (7.0 gm.) could not be recrystallised and was extracted with dry acetone in a Soxhlet apparatus, whereby 3.3 gm. greyish solid was obtained. After charcoalizing in alcohol solution, recovery of the solid, and two crystallisations from methanol and ethyl acetate 1.75 gm. (21%) white powder was obtained, M.P. 224–5° C. dec.; chlorine content 8.49% as compared with the theoretical value of 8.61%.

Example 4.—2-thenoylmethylbenzoyl-pseudo-tropinium bromide

Benzoyl-pseudo-tropine (4.90 gm., 0.02 M) and 2-bromacetylthiophene (4.50 gm., 0.022 M) were refluxed 5 hours in 50 ml. dry acetone. On cooling and filtering 8.1 gm. (91%) cream coloured solid was collected, M.P. 214–216° C. After recrystallisation from aqueous alcohol, washing with acetone and drying at 80° C. in vacuo the yield of pure material was 5.6 gm. (62%), M.P. 223–4° C. Assay by determination of bromine indicated a purity of over 99%.

By substitution of other esters of pseudo-tropine for the benzoyl-pseudo-tropine mentioned in the above example, the following were obtained:

15 2-thenoylmethylphenylacetyl-pseudo-tropinium bromide—M.P. 185–6° C.
20 2-thenoylmethylisobutyryl-pseudo-tropinium bromide—M.P. 193–4° C.

Example 5.—2-pyrrolylmethyl phenylacetyl-pseudo-tropinium bromide

Phenylacetyl-pseudo-tropine (2.60 gm., 0.01 M) and 2-chloroacetylpyrrole (1.30 gm., 0.01 M) were refluxed 4 hours in 10 mls. dry acetone. On cooling no solid separated. The crude quaternary was therefore poured into excess ether and the greyish solid thus obtained was charcoaled in 10% aqueous solution. After filtration a concentrated solution of potassium bromide was added, producing a white precipitate of the quaternary bromide, M.P. 181–2° C., not altering on further crystallisation and having a bromine content of 18.12% against the calculated figure of 17.90%.

Example 6.—2-furoylmethyl phenylacetyl-pseudo-tropinium bromide

Phenylacetyl-pseudo-tropine (11.5 gm.) and 2-bromacetyl furan (9.2 gm., 10% excess) were refluxed two hours in 120 ml. of methylethylketone. On cooling, the amount of crude material collected was 15.1 gm. (76% yield). This, after crystallisation from ethanol/ethylacetate weighed 13.5 gm. (68%), M.P. 180–1° C., and had a bromine content of 17.24% as compared with the theoretical figure of 17.32%.

It is convenient to employ the quaternary salts of the present invention as hypotensive agents in the form of simple aqueous solutions. It is desirable that these solutions should be kept out of strong daylight; for example they should be contained in amber coloured ampoules and preferably stored in the dark. The quaternary salts are conveniently supplied in ampoules containing a 5% weight by volume solution. This is intended to be diluted twenty to one hundred times for use in controlled intravenous infusion. The 5% solution is sensitive to direct sunlight, decomposition occurring with formation of a deposit. It is stable in the dark and does not readily decompose in diffused daylight.

In using the quaternary salts for reduction of blood pressure during a surgical operation, an aqueous solution containing from 0.5 to 2.5 mg. per ml. may be administered as an intravenous drip. Hypotension can be achieved in a space of two to ten minutes depending on the rate of administration. The desired degree of hypotension can be maintained for prolonged periods by continued administration at a slow rate and recovery is rapid. Operations can be carried out using total quantities varying from 50–500 mgms. The action can readily be reversed by the administration of, for example, methedrine, 2 mgms.

We claim:

70 1. A quaternary halide of the general formula:

wherein Hal represents a halogen atom, Y represents the acyl radical of an organic carboxylic acid selected from the group consisting of mandelic, phenylacetic, benzoic, tropic and isobutyric acids, and D represents a divalent member selected from the group consisting of —S—, 5 —O— and —NH—.

2. 2-thenoylethyl homatropinium halide salt.
3. 2-furoylethyl homatropinium halide salt.
4. 2-pyrroylethyl homatropinium halide salt.
5. 2-thenoylethyl benzoyl-pseudo-tropinium halide salt. 10
6. 2-thenoylethyl homatropinium bromide.
7. 2-thenoylethyl phenylacetyl-tropinium bromide.
8. A liquid for intravenous injection to produce hypotension consisting essentially of a solution in water of 0.5 to 2.5 mgms. per ml. of 2-thenoylethyl homatropinium bromide.
9. The process of preparing a quaternary halide which comprises reacting a heterocycloylethyl halide of the general formula: 15

wherein D represents a member selected from the group 25

consisting of —S—, —O— and —NH—, and Hal represents a halogen atom, with an ester of the general formula:

wherein Y represents the acyl radical of an organic carboxylic acid selected from the group consisting of mandelic, phenylacetic, benzoic, tropic and isobutyric acids.

10. The process as claimed in claim 9 wherein the organic carboxylic ester is homatropine.
11. The process as claimed in claim 9 carried out in presence of an inert solvent for the reagents.
12. The process as claimed in claim 9 carried out in the presence of a polar solvent.
13. The process as claimed in claim 9 carried out in presence of a ketone as polar solvent.
14. The process as claimed in claim 9 in which heating 20 is employed.
